UNITED STATES PATENT OFFICE.

ALBERT B. FRENIER, OF DAVENPORT, IOWA.

WHEELED PLOW.

No. 856,240.

Specification of Letters Patent.

Patented June 11, 1907.

Application filed December 17, 1903. Renewed November 10, 1906. Serial No. 342,906.

To all whom it may concern:

Be it known that I, ALBERT B. FRENIER, a citizen of the United States of America, and a resident of Davenport, Scott county, Iowa, have invented a certain new and useful Improvement in Wheeled Plows, of which the following is a specification.

My invention relates to wheeled plows in general, but more particularly to that type of plow in which a suitably wheeled body-frame is provided, and in which the plow and beam are adjustably supported from the said body-frame.

In application No. 185,470 of even date herewith, I have elected to claim my invention broadly, while in the present application I have claimed only the hereinafter described specific form of my invention. In practice, I find that for some purposes and with some users the construction disclosed in my said other application is preferable, while for other purposes and with other users the construction herein shown and described is preferable.

Generally stated, the object of my invention is to provide an improved arrangement of foot-levers for lifting and depressing the plow.

A special object is to provide a construction and arrangement whereby the two foot-levers can be supported by a housing or bracket mounted on the body-frame, rather than by the wheel axle and, if desired, employed in conjunction with a hand-lever mounted upon the land-side axle at a point adjacent to the land-side wheel.

It is also an object to provide certain details and features of improvement tending to increase the general efficiency and serviceability of a plow of this particular character.

To the foregoing and other useful ends, my invention consists in matters hereinafter set forth and claimed.

In the accompanying drawings, Figure 1 is a side elevation of a wheeled-plow embodying the principles of my invention, the plow being shown in its lowered working position. Fig. 2 is a similar view, but showing the plow in an elevated position. Fig. 3 is a plan of the plow shown in Fig. 1. Fig. 4 is an enlarged side elevation of the double foot-lever arrangement for lifting and depressing the plow, showing the plow-beam in a depressed position. Fig. 5 is a view similar to Fig. 4, but showing the plow-beam in an elevated position. Fig. 6 is an enlarged detail of the

hub portion of the depressing foot-lever. Fig. 7 is an enlarged longitudinal section through the bearing sleeve for the rock-shaft upon which the lifting lever is mounted, and also through the hub portion of the depressing lever, said shaft being shown in elevation. Fig. 8 is an enlarged detail view of the inner side of the toggle arm which constitutes a part of the toggle connection between the plow-beam and the rock-shaft upon which the lever is mounted, showing the shoulders between which the lug on the depressing lever plays, this lug and the two shoulders constituting the aforementioned lost motion connection between the depressing lever and the rock-shaft for raising and lowering the plow-beam.

As thus illustrated, the general construction of the plow involves the usual body-frame A, mounted upon supporting wheels B, C and D. The wheels B and C are respectively front and rear furrow-wheels, of the usual and well known character, while the wheel D is the usual land-side wheel. The said forward furrow-wheel B is mounted on the lower outturned end portion of the stem b, which latter extends upwardly through a bracket bearing b' secured to the body-frame. Thus, through the medium of the hand-lever E having a link connection e with a casting e' fixed to the upper end of the said stem, the lever being pivoted to the said bracket-bearing b', it is possible to manually raise and lower the forward portion of the body-frame upon the said furrow-wheel stem b. The lever E can be provided with the usual spring-held locking device e² adapted to engage a toothed-rack e³ secured to or rigid with the bracket bearing b'. If desired, the rotary or oscillatory stem c can have its upper end connected with the stem of the forward furrow-wheel through the medium of a rod c'. The latter can have its forward end adapted to engage the slot c² in the top casting e'. With this arrangement, the tongue F, which is secured in any suitable manner to the casting e', controls the forward furrow-wheel, and also, when the plow is running straight ahead, prevents turning or lateral play of the rear furrow-wheel. But as soon as the tongue is swung to one side, then the forward end of the rod c' slides in the slot c², thereby releasing the rear furrow-wheel, and allowing the latter to turn or easter freely in the usual and well known manner. The driver's seat G can be secured to or supported upon the rear por-

tion of the body-frame in any suitable or desired manner.

The land-side wheel D is mounted upon the spindle carried at the end of the crank-arm d, which latter constitutes the outer-end portion of the crank-axle d', the latter being in turn mounted to rock in a bracket-bearing d². This bearing, as will be observed, is rigidly secured to the land-side of the body-frame A. Another hand-lever H is mounted upon the said land-side axle d', and provided with the usual locking device adapted to engage the toothed rack h. The latter being rigidly secured to the bracket d², constitutes the means for rocking this land-side axle for the purpose of raising and lowering the body-frame or swinging the plow, or throwing the plow out of the furrow. Preferably, as illustrated, the said lever H is yieldingly connected with the land-side axle through the medium of the spring h', which is mounted for compression between the crank-arm h², rigidly secured to the land-side axle, and the part h³ suitably connected with the said lever. In this way, the lever, as stated, is secured to but has a yielding connection with the land-side axle, whereby, when the lever is locked in engagement with the rack h, the land-side wheel is capable of more or less up-and-down movement relative to the body-frame, so as to insure a cushioning action or effect when the land-side wheel passes over obstructions or uneven surfaces. Thus it will be seen that, through the medium of the two hand-levers E and H, and their connections, respectively, with the forward furrow wheel and the land-side wheel, these two wheels can be controlled, each independently of the other, for the purpose of manipulating the plow in the well known manner, by reason of the raising and lowering of the forward portion of the body-frame relatively to the said wheels.

The plow or implement I can be of any suitable, known or approved form, and can be provided with the usual plow-beam J. Also, the plow can be hung from the body-frame in any suitable known or approved manner. For example, the front and rear bails K and L, devices well known in the art, can be employed as a medium of swinging or shifting connection between the plow-beam and the body-frame; it being observed that these bails have their end portions mounted to turn in suitable bearings on the body-frame, and having their forward or middle portions mounted to turn in suitable bearings on the plow-beam. With this arrangement, the plow, in rising, swings up and slightly backward, and, in descending, swings down and slightly forward.

The features thus far described are well known and do not, therefore, need any further description.

65 It is the double foot-lever arrangement for

lifting and depressing the plow to which my invention relates; and, as previously stated, it is the specific construction of this arrangement, by which an arrangement of parts substantially different from that shown in my 70 said other application, and by which different disposition of the means for rocking the land-side axle, are obtained, that is herein-after described and claimed.

The bracket-bearing d² is preferably rigid with the transversely disposed housing or bearing M. This housing or bearing, as illustrated, is sufficiently long to provide a bearing of suitable length for the rock-shaft N, which latter constitutes a part of the lifting and lowering connection between the plow-beam and the lifting foot-lever O. This lifting foot-lever is, it will be seen, rigidly secured to the outer end of said rock-shaft, and, when the plow is in a depressed position, projects rearwardly, as shown in the drawings. The other end of said rock-shaft is provided with a crank-arm n adapted to serve as part of the toggle connection between the said rock-shaft and the plow-beam. 80 In other words, this crank-arm n and the link n', constitute a jointed or toggle-like connection between the rock-shaft and plow-beam. The lower-end of this toggle-like connection is pivoted to the plow-beam at n², preferably 85 through the medium of a bracket-plate P. This bracket-plate is preferably adjustably mounted upon the plow-beam by reason of its being provided with slots through which are inserted the attaching bolts p. In this 90 way, the said bracket-plate can be adjusted longitudinally of the plow-beam for the purpose of insuring an accurate adjustment and disposition of the various parts and connections. In order that the said toggle-like 95 connection may buckle or break-joint readily in an upward direction, when the plow strikes a stone or other obstruction, the arm n is provided with an adjustable stop n³ 100 adapted to bear against the forward or upper edge of the link n'. Thus, by adjusting this stop in the proper manner, the said toggle-like connection can be prevented from straightening out to an extent to bring its joint or intermediate pivotal connection n⁴ to a point 105 below the center—that is to say, to an extent to prevent its joint from falling below a line drawn from the center of the rock-shaft N through the pivotal point n². With this provision, therefore, it is evident that the 110 said toggle-like connection does not positively lock the plow in the ground. The depressing lever Q is, it will be seen, provided with a separate mounting, being formed with an enlarged hub-portion q, which is mounted 115 to turn or oscillate upon the housing M. In this way the depressing lever is loose relatively to the rock shaft. When the plow is in the ground, this depressing lever projects 120 forward, as shown in Fig. 4; and by refer- 125

ring to Fig. 6, it will be seen that this depressing lever is provided with a lug q' , adapted to project and play between the shoulders n^5 formed on the hub-portion of the crank-arm n . In this way, the depressing lever cannot communicate any power or motion to the rock-shaft N , or to the plow-beam through the toggle connection, until the lost-motion is taken up, one way or the other. The hub portion of the depressing lever Q is provided with a rearwardly extending arm q^2 , adapted, when the plow is lowered into the ground, to have its rear end raised to a point slightly above the axis about which the depressing lever swings. In this way, the combined lifting and depressing spring R , which is connected between the forward portion of the body-frame and the said arm q^2 , through the medium of the bent link r , can be employed as a means for not only assisting the lifting lever in raising the plow off from the ground, but also as a means for yieldingly maintaining the plow in the ground. The link r is, it will be observed, adapted to connect the rear end of the spring R with the arm q^2 , the link and arm being pivotally connected at their rear ends by means of bolts or pins r . With this provision, the plow is adapted to operate as a stone dodger, the tension of the spring R being sufficient to keep the plow in the ground as long as no obstructions are encountered. The depressing lever is further provided, preferably, with a locking projection or hook q^3 , which is rigidly mounted upon or formed integrally with the hub of said depressing foot-lever. This hook or locking projection q^3 is adapted, when the plow is raised into the position shown in Fig. 5, to engage the lug or projection p' on the bracket plate P . In this way, the hook q^3 and the lug p' constitute mutually engaging elements for locking the plow in its elevated position.

The mode of operation is obvious: When it is desired to release the plow and allow the latter to descend to the ground, the driver exerts foot pressure upon the lever Q , thereby disengaging the hook q^3 from the lug p' , so as to allow the plow to swing down; and, owing to the separate and independent mountings for the two foot-levers, and the lost motion connection between the depressing foot-lever and the rock-shaft, without communicating any power or motion through the toggle-connection to the plow-beam. As soon as the locking device is thus unlocked, the weight of the plow is sufficient to carry it down to the ground, the tension of the spring being counteracted by foot pressure on the lever Q . When the plow reaches the ground, the continued foot-pressure on the lever Q takes up the lost motion between this lever and the rock-shaft N , thereby enabling the spring R to shift from lifting to depressing position, as a result of motion of the depressing lever, independently of the lifting lever, and independently of the toggle-connection between the lifting lever and the plow-beam. In other words, the independent movement of the depressing lever, by thus taking up the lost motion, brings the pivotal point r' to a point just above a line drawn from the center of the rock-shaft N to a point where the forward end of the spring is attached to the body-frame. This, obviously, enables the spring to exert its tension in a reverse direction on the plow-beam, its pull or tension now tending to rotate the rock-shaft in a direction to straighten out the toggle-connection, and thereby force the plow into the ground. In this way, the separate mounting and independent action of the two foot-levers not only permits the plow to be unlocked from its elevated position without exerting any downward pressure on the plow through the toggle-connection, but it also permits the spring to be easily shifted from lifting to depressing position. That is to say, the shifting of the spring from lifting to depressing position, is accompanied by a free and independent movement on the part of the depressing lever. Now suppose it is desired to lift the plow from the position shown in Fig. 4 to the position shown in Fig. 5. In such case, the driver exerts a foot-pressure on the lifting lever O , thereby causing the toggle-connection to exert an upward pull on the plow-beam. The initial downward movement of the lifting foot-lever O , in this manner, is, it will be seen, sufficient to bring the pivotal connection r' to a point coincident with or slightly below the aforementioned line drawn from the center of the rock-shaft N to the point where the spring R is connected with the body-frame; and when the pivotal point r' is thus shifted to a point slightly below the center, so to speak, the spring R then instantly takes up the lost-motion between the hub portion of the depressing lever and the rock-shaft, and in so doing gives the arm q^2 a substantial downward swing or movement relatively to the lifting lever. That is to say, the spring, when the plow is started on its upward movement, suddenly takes up the lost-motion, and thereby avails itself of the increased leverage which results from the quick shift of the arm q^2 to a lower position. This, it will be seen, makes it unnecessary for the lifting foot-lever to be swung downward to quite an extent in order to permit the spring to pull with sufficient power to assist in lifting the plow, the initial downward movement of the lifting lever being sufficient to establish such conditions as well as enable the spring to contribute materially to the power necessary for lifting the plow to its elevated position. In other words, the lifting of the plow and the shifting of the spring from depressing to lifting position, are necessarily and advan-

tageously accompanied by independent movement of the depressing lever relatively to the lifting lever and toggle connection. A further depression of the foot-lever O to the position shown in Fig. 5, is sufficient to bring the locking hook q^3 into engagement with the lug p^3 ; and, owing to the relative arrangement of the different parts, it will be seen that the plow cannot then be lowered unless foot-pressure is applied to the depressing lever Q.

Thus it will be seen that I provide a simple and efficient double foot-lever arrangement for lifting and lowering the plow, and combine the same with a combined lifting and depressing spring, whereby spring tension is employed both for lifting and depressing the plow. Furthermore, with the foot-levers arranged as shown, the lever H for independently manipulating the land-side wheel, can be arranged at the left of the plow, or at a point adjacent to the land-side wheel, as shown in the drawings. The land-side axle supports only the one lever by which it is operated.

The object and function of the lost-motion connection provided between the separately mounted portions of the two foot-levers, is simply this: The combined lifting and depressing spring can be shifted from a lifting to a depressing position, and vice versa, through the medium of a certain amount of adjustment or movement on the part of the depressing lever independently of the other lever, and without communicating any power or motion to the plow through the toggle-like or other jointed connection; and, further, this lost-motion connection permits of a downward adjustment or movement on the part of the locking element, which is rigid with the depressing lever, before any power or motion is communicated to the plow through the said toggle-like connection; but the shifting of the combined lifting and depressing spring, so that it will pull either above or below the center, as it may be desired to depress or lift the plow, is the principal object or function of the lost-motion connection; for while its provision makes it somewhat easier to unlock the plow, it is obvious that the locking arrangement would be operative without the provision of any relative movement whatever between the two foot-levers.

With the provision of the combined lifting and depressing spring, the depressing lever is not necessarily a depressing device in the sense of permitting the plow to be manually pushed into the ground, as the function of the lever is merely to shift the spring, and lower its rigid locking element out of engagement with the lug on the plow-beam, the spring and toggle constituting the means for pushing down on the plow as the plow-point catches and enters the ground.

What I claim as my invention is:

1. A wheeled-plow comprising a body-frame, supporting wheels, a plow and beam movably supported from the body-frame, a bracket bearing mounted on the body-frame, lifting and depressing foot-levers separately mounted on said bearing and adapted for some movement independently of each other, and a toggle-connection between the said lifting lever and the plow-beam, the two associated foot-levers being axially alined and having a lost-motion connection between them, whereby a portion rigid with the lifting foot-lever constitutes medium of connection through which motion is communicated from the depressing foot-lever to the plow.

2. A wheeled-plow comprising a body-frame, supporting-wheels, a plow and beam movably supported from the body-frame, a housing rigidly mounted upon the body-frame, a rock-shaft mounted to turn in said housing, a lifting foot-lever rigid with said rock-shaft, a toggle-like connection between said rock-shaft and the plow-beam, and a depressing foot-lever mounted on said housing and adapted for some movement independently of said lifting lever, the two associated foot-levers being axially alined and having a lost-motion connection between them, whereby a portion rigid with the lifting foot-lever constitutes medium of connection through which motion is communicated from the depressing foot-lever to the plow.

3. A wheeled-plow comprising a body-frame, supporting wheels, a plow and beam movably supported from the body-frame, a housing or bracket rigidly mounted upon the body-frame, a rock-shaft mounted to turn in said housing, a lifting foot-lever mounted on the housing or bracket and rigid with said rock-shaft, a toggle-like connection between said rock-shaft and the plow-beam, a depressing foot-lever also mounted on said housing or bracket and adapted for some movement independently of the lifting lever, said depressing lever being loose relatively to the rock shaft, and a locking device for locking the plow-beam in an elevated position, the said locking device being adapted to be unlocked by movement of the depressing lever the two associated foot-levers being axially alined and having a lost-motion connection between them, whereby a portion rigid with the lifting foot-lever constitutes medium of connection through which motion is communicated from the depressing foot-lever to the plow.

4. A wheeled-plow comprising a body-frame, supporting wheels, a bearing rigid with the body-frame, a plow and beam, a rock-shaft mounted in said bearing, a toggle-connection between the rock-shaft and the plow-beam, a lifting foot-lever rigid with the rock-shaft, a depressing foot-lever mounted on the bearing and adapted for some move-

- ment independently of the lifting lever, and a combined lifting and depressing spring connected to exert a pull upon a part rigid with the depressing lever, said spring being adapted to be shifted from lifting to depressing position, and vice versa, through the medium of the independent movement of the depressing lever the two associated foot-levers being axially alined and having a lost-motion connection between them, whereby a portion rigid with the lifting foot-lever constitutes medium of connection through which motion is communicated from the depressing foot-lever to the plow. 50
5. A wheeled-plow comprising a body-frame, supporting wheels, a plow and beam, a bearing mounted on the body frame, lifting and depressing levers separately mounted on said bearing and adapted for some movement independently of each other, a toggle-connection between the lifting lever and the plow-beam, a combined lifting and depressing spring connected to exert a pull upon a portion rigid with the depressing lever, such 55 spring being adapted to be shifted from lifting to depressing position, and vice versa, through the medium of the independent movement of the depressing lever, and a hand-lever located at the left of said foot-levers and adapted for manipulating or controlling one of said wheels relatively to the body-frame the two associated foot-levers being axially alined and having a lost-motion connection between them, whereby a portion rigid with the lifting foot-lever constitutes medium of connection through which motion is communicated from the depressing foot-lever to the plow. 60
6. A wheeled-plow comprising a body-frame a bracket on the left side of the frame a plow and beam, supporting wheels including a land-side wheel, separated and suitably mounted lifting and depressing foot-levers carried by the bracket on the body-frame, a connection between the plow-beam and the said lifting lever, a lost-motion connection between the two foot-levers, and a hand lever adapted for manipulating said land-side wheel, the hand-lever being mounted be- 65
- tween the land-side wheel and the foot-levers the two associated foot-levers being axially alined, and a portion rigid with the lifting foot-lever constituting medium of connection through which motion is communicated from the depressing foot-lever to the plow. 70
7. A wheeled-plow comprising a body-frame, supporting wheels including a land-side wheel, a plow and beam, a bearing mounted on the body-frame, lifting and depressing foot-levers separately mounted on said bearing, a lost-motion connection between said foot-levers, a toggle-connection between the lifting lever and the plow-beam, a combined lifting and depressing spring connected to exert a pull upon a portion rigid with said depressing lever, and a hand-lever adapted for controlling the land-side wheel relatively to the body-frame, the said hand lever being mounted between the land-side wheel and the foot levers the two associated foot-levers being axially alined, and a portion rigid with the lifting foot-lever constituting medium of connection through which motion is communicated from the depressing foot-lever to the plow. 75
8. The improved wheeled plow with lifting and depressing foot levers mounted separately upon a bracket bearing secured rigidly to the frame of said plow the two associated foot-levers being axially alined and having a lost-motion connection between them, whereby a portion rigid with the lifting foot-lever constitutes medium of connection through which motion is communicated from the depressing foot-lever to the plow. 80
9. The improved wheeled plow comprising a plow and beam; supporting wheels, a rigid bracket and two levers mounted for more or less separate and independent operation, and supported separately upon the said bracket, 85 substantially as described.

Signed by me at Rock Island, Rock Island county, Illinois, this 27th day of November, 1903.

ALBERT B. FRENIER.
